US00D855015S

(12) **United States Design Patent** (10) **Patent No.:** **US D855,015 S**
(45) **Date of Patent:** **** Jul. 30, 2019**

(54) **TIRE SPOKES**

(71) Applicant: **Bridgestone Americas Tire Operations, LLC**, Nashville, TN (US)
(72) Inventors: **Ali Manesh**, Chicago, IL (US); **Mike Tercha**, Weston, WI (US); **Karen Schleis**, Wasau, WI (US); **Brian Meliska**, Weston, WI (US); **Louis Stark**, Kronenwetter, WI (US); **Fidelis Ceranski**, Marathon, WI (US); **Glenn Howland**, Kronenwetter, WI (US)

(73) Assignee: **Bridgestone Americas Tire Operations, LLC**, Nashville, TN (US)

(**) Term: **15 Years**

(21) Appl. No.: **29/662,002**

(22) Filed: **Aug. 31, 2018**

Related U.S. Application Data

(63) Continuation of application No. 13/333,721, filed on Dec. 21, 2011, now Pat. No. 10,086,654, which is a continuation of application No. 12/055,675, filed on Mar. 26, 2008, now Pat. No. 8,109,308, which is a continuation-in-part of application No. 11/691,968, filed on Mar. 27, 2007, now Pat. No. 8,104,524.

(57) **CLAIM**

The ornamental design for tire spokes, as shown and described.

DESCRIPTION

FIG. 1 is a side elevational view of tire spokes; and, FIG. 2 is a perspective view of tire spokes. The broken lines defining the tire tread represent unclaimed environmental subject matter and form no part of the claimed design.

1 Claim, 2 Drawing Sheets
